Primary Examiner — Richard Kearney*Assistant Examiner* — Benjamin M Weeks(74) *Attorney, Agent, or Firm* — Kunzler Bean & Adamson(57) **CLAIM**

The ornamental design for a bracket for electronic equipment, as shown and described.

DESCRIPTION

FIG. 1 is a three-dimensional view of the top surface of the bracket for electronic equipment;

FIG. 2 is a three-dimensional view of its bottom surface;

FIG. 3 is the plan view of its front;

FIG. 4 is the plan view of its back;

FIG. 5 is the plan view on its left side;

FIG. 6 is the plan view on its right side;

FIG. 7 is the plan view of its top surface; and,

FIG. 8 is a plan view of its bottom surface.

The broken lines in the drawings illustrate the portions of the bracket for electronic equipment, which form no part of the claimed design.

1 Claim, 8 Drawing Sheets(56)
